UNITED STATES PATENT OFFICE.

FRANK M. CLARK, OF TILTON, NEW HAMPSHIRE, ASSIGNOR OF ONE-HALF
TO WILLIAM I. HOLMES, OF BOSTON, MASSACHUSETTS.

WOVEN FABRIC.

SPECIFICATION forming part of Letters Patent No. 642,084, dated January 30, 1900.

Application filed August 19, 1898. Serial No. 689,029. (No specimens.)

To all whom it may concern:

Be it known that I, FRANK M. CLARK, of Tilton, county of Belknap, and State of New Hampshire, have made certain new and useful Improvements in Woven Fabrics, of which the following is a description sufficiently full, clear, and exact to enable any person skilled in the art or science to which said invention appertains to make and use the same, reference being had to the accompanying drawings, forming part of this specification, in which—

Figure 1 is a plan view showing a portion of the warp-threads with the filling-threads at opposite sides of the warp in position to be carried through; Fig. 2, a like view showing the first movement of carrying one filling-thread through the warp; Fig. 3, a plan showing the completion of this movement; Fig. 4, a similar view showing the position of the strands when the reed has laid this thread; Fig. 5, a view like that in Fig. 2, showing action of the filling-thread in the next following movement; Fig. 6, a view like that in Fig. 3, showing the thread cut and in the warp; Fig. 7, a plan showing the cut thread after being laid by the reed; Fig. 8, a plan of a section of the completed cloth; Fig. 9, an edge view of the same.

Like letters of reference indicate corresponding parts in the different figures of the drawings.

My invention relates especially to a weave of cloth or other fabric in which there is a novel combination of the warp and filling or weft threads whereby an excellent even selvage is produced on both edges of the cloth without forming listing or the employment of what are commonly known as "selvage-threads" or of binders other than the ordinary outer threads of the warp.

The nature of the improvement and the method whereby it is produced will be understood by those skilled in the art from the following explanation:

In the drawings, *a a* represent the outer, and *b b* the intermediate, warp-threads, this distinction being made solely to facilitate explanation of the weave; but it should be understood that all the warp-threads perform like functions—that is, the threads *a* do not

represent "padding" or listing warps. *d* represents the weft-thread at one side of the cloth, and *f* the weft-thread at the opposite side.

I will first describe the laying of a pick from one filling-thread *d*, the parts being in the position shown in Fig. 1. The end *q* of the filling-thread *d* is held in any suitable device and passes nearly in parallelism with the adjacent outer warp-thread *a*, as in Fig. 1, to the bobbin. There are the ordinary number of threads in the warp for the width of the main cloth-body, no additions being made for listing or selvage. In the first movement at 65 starting the filling *d* is projected double under and over the alternate warp-threads *a b* until one-half way across the warp in an approximate V shape, as shown in Fig. 2, the end *q* being still held. At this point the end 70 *q* is let go and thus freed is carried through the remaining warps until said end has passed the outer warp *a* at the opposite side, the positions assumed being shown in Fig. 3. The tension of the warp-threads that have engaged 75 the filling *d* during the first half of its course described is sufficient to prevent more being drawn in from the bobbin after the end *q* has been thus released and projected the balance 80 of the course. Now the thread *d* lies diagonally across the warp, as in Fig. 3. The reed beats and lays the filling thus projected into its path in line at right angles to the warp, as in Fig. 4, this movement being the ordinary one. The body of this thread is by this 85 movement again disposed in substantially its original position outside the outer warp *a*, as shown in said Fig. 4. Now again is the body of the filling *d* entered double over adjacent warp *a* and under the adjacent warp *b*, as in 90 Fig. 5, alternating until the apex of said V portion is one-half across said warp. At this instant the filling *d* is held by suitable means at *v*, and simultaneously said filling is cut at *t*, Fig. 5, leaving the main end *v* held, as in 95 Fig. 6. The severed end *w* is carried through the rest of the warps and left in the diagonal position shown in Fig. 6. This is beaten up by the lay, as shown in Fig. 7. The retained end *v* of the filling *d* is then carried forward 100 into its original position, as in Fig. 7, this end *v* being the equivalent of the first-de-

scribed end q , when the second pick is thereafter made from this side of the warp. It will thus be seen that instead of the filling being carried across the warp and returned, as when 5 an ordinary shuttle-weave is employed, two picks consisting of a single strand cut from the main thread are laid from the same side of the warp, that also said severed portion passes around or astride of the outer warp-thread a at x , Fig. 8, on the side at which the thread is delivered, and that the severed ends overlap slightly the outer warp-thread a at the opposite side of the fabric, one, q , below and the other, w , above said outer warp-thread, 10 and now at the opposite side of the warp the other filling-thread f is entered in identically the same manner for two picks in the warp as described in disposing filling d , the position of its severed ends q^2 and w^2 being at 15 the opposite edge of the warp. It will thus be seen that two picks are laid consecutively from one side of the warp and then two picks from the opposite side of said warp. Each 20 set of two picks consists of a separate **U**-shaped strand of filling, the loop of the **U** passing around the outer warp-thread and its arms being respectively disposed in adjacent sheds and terminating together at the 25 opposite edge of the fabric—that is, there is 30 no other filling-thread laid between the arms of said **U**-shaped strand. The cloth resulting is of the pattern shown in Figs. 8 and 9. No extra binding, listing, or selvage threads are employed in my improved cloth, the cut 35 ends being held by the outer warp and the loops α encircling said outer warp alternately with each pair of ends. Thus without padding the warp—that is, employing extra warp-threads in addition to those required in the 40 determined width of the cloth in order to weave the filling into said extra warp-threads

in distorted manner for the purpose of locking said filling and forming a listing or selvage that must be torn off in use—I weave the width of cloth desired and form a selvage by 45 putting in two picks consecutively from the same side of the warp, said two picks being formed from a single strand of filling looped centrally around the outer warp-thread. This, as shown, occurs at the same edge of the 50 fabric with each alternate set of two picks. This effect is impracticable with an ordinary shuttle-weave.

Having thus explained my invention, what I claim is—

1. A fabric comprising warp-threads and interwoven filling-threads, said filling-threads being composed of **U**-shaped strands inserted alternately from opposite sides of the warp, the loop of each strand encircling the outer 60 warp-thread and the arms of said strand being respectively disposed in adjacent sheds without other filling material between, substantially as described.

2. A fabric comprising warp-threads and 65 interwoven filling-threads, said filling-threads comprising **U**-shaped strands inserted alternately from opposite sides of the warp, the two arms of each **U**-shaped strand being respectively laid in next adjacent sheds without other filling material between said arms, the loop of said strand encircling the outer warp-thread at the side from which its arms are thus inserted, and the ends of said arms terminating at the opposite outer warp-thread 70 without being encircled by an adjacent filling-strand loop substantially as specified.

FRANK M. CLARK.
